UNITED STATES PATENT OFFICE

PAUL W. ENSIGN, OF SAN MARINO, CALIFORNIA, ASSIGNOR TO ENSIGN CARBURETOR CO. LTD., OF HUNTINGTON PARK, CALIFORNIA, A CORPORATION OF CALIFORNIA

CARBURETOR

Application filed November 25, 1930. Serial No. 498,040.

This invention has to do with carburetors; and, among other objects, has for its object the production of a universal carburetor capable of producing most highly efficient results for all types of engines and for all engine operating conditions.

It is well known in the art that carburetors, in order to operate with efficiency, must be designed and adapted to the particular "job" intended. A carburetor which operates with satisfaction on an engine of given size will not operate satisfactorily on another size, even though smaller. The carburetor adapted to an eight cylinder engine will not give satisfactory results, without redesigning, on a six cylinder engine. These things hold true even for slight differences in suction curves, manifold arrangements, and many other details in which one engine may differ from another.

And, when a carburetor is designed efficiently for a particular "job", and used on that one only, it has been shown by experience necessary to provide in the carburetor numerous modifying arrangements, adapted to modify in various manners the many fuel-and-air functions of the carburetor, in order to attain efficiency even on that single job.

A general object of this invention is the production of a carburetor which overcomes these and other defects and shortcomings of previous carburetors; to provide a carburetor which need not be specially designed for various engines and which, although simple in construction and operation, produces results of maximum efficiency. It is also an object to produce an efficiency greater in practical operation than that of any previous carburetor of which I am aware.

There are also various other objects, and the invention has corresponding characteristics, as will be best understood from the following description. A major characteristic of the invention here described resides in its use of a metering venturi whose depression is utilized to meter fuel, without any interference with the theoretic venturi function. A Venturi tube is one of the most accurate known devices for measuring or indicating the flow of fluid through it. In present car-

buretors fuel is commonly drawn from the fuel supply by the depression at the Venturi throat; but such carburetors commonly discharge the fuel into the Venturi throat where vaporization and expansion of the fuel interferes very substantially with accurate and efficient Venturi action. A characteristic of my invention is that the fuel is metered by Venturi action which is not obstructed or modified in any manner, and that the fuel so initially metered does not at any time pass through that venturi on its way to the air stream. To prevent the flow of fuel to the metering venturi, I provide in this carburetor a system of maintaining a differential depression between the venturi and the fuel nozzle or fuel nozzle passage; so that the initially metered fuel is carried on to the fuel nozzle and there, preferably in admixture with air, thrown into the main air stream.

The differential fuel feeding depression just above referred to may be and preferably is of substantial amount, without interfering with the Venturi control of initial metering. This substantial differential depression aids very materially in discharging fuel with such violence into the main air stream that the fuel is thoroughly and finely atomized.

And the arrangements for creating the differential depression also lend themselves most readily to a peculiarly efficient accelerating operation as will be hereinafter described. A characteristic of the accelerating operation is that, instead of causing the feed of additional accelerating fuel to lag behind the flow of increased air passing through the carburetor, my arrangement tends to retard momentarily the increased flow of air and to accelerate the increased flow of fuel; which results in a most effective accelerating mixture.

The carburetor herein described also lends itself very readily to the application of a simple idling system, as will be described; and, generally speaking, the invention provides a carburetor of great simplicity, not requiring many of the small complications now found necessary in present carburetors.

In order to set out my invention I shall

describe in detail certain illustrative and typical structures embodying the invention, and then describe the characteristics of operation illustrated in those structures. I wish it to be understood, however, that the invention is not limited either to the described structures or to the functions set out, except as expressly so stated in the appended claims.

10 The invention here claimed has certain features in common with a prior fuel converter, for which I and Roy F. Ensign have filed application Ser. No. 170,182 on February 23, 1927. For that invention the broad 15 characteristic of metering fuel by Venturi depression is utilized; but in conjunction with a fuel converting as well as carbureting device. Insofar as there is common patentable subject matter between the two cases, 20 the broader common claims will be carried in said prior application; leaving to the present application the claims having to do with application of the broader characteristics to carburetion, and the attendant developments 25 and improvements.

Typical structures

Figure 1 is a more or less diagrammatic view showing one form of my improved carburetor. In this view certain parts, as will be explained later, are for clarity of illustration and simplicity of description, shown in positions other than those actually occupied in the manufactured carburetor; 35 Fig. 2 is a detail section on line 2—2 of Fig. 1 showing particularly the economizer port;

Fig. 3 is a detail section showing a modification of certain parts as shown in Fig. 1;

40 Fig. 4 is a similar detail section showing other modifications of those same parts;

Fig. 5 is a detail section of the same parts of Fig. 1 but showing the structure as it has been made, whereas Fig. 1 shows diagrammatic arrangement of the structure;

45 Fig. 6 is a detail section on line 6—6 of Fig. 5;

Figs. 7 and 8 are detail sections showing certain parts of Fig. 1 in other operating positions, and showing the idling valve mechanism of Fig. 9. Fig. 1 shows the parts of the carburetor as operating wide open, Fig. 7 shows the parts in idling position, and Fig. 8 shows the parts in an intermediate 55 position;

Fig. 9 is a sectional view similar to Fig. 1 but showing another form of carburetor as will be explained;

Fig. 10 is a detail section taken as indicated by line 10—10 on Fig. 9;

Fig. 11 is a view similar to Fig. 7, showing a slightly modified form of venturi; and

Fig. 12 is a view similar to Fig. 8 showing the modified form of Fig. 11.

45 Referring first to Figs. 1, 5 and 6 I show

therein a suitable carburetor structure which includes a constant level fuel chamber 10 in which the fuel level is controlled by float 11 and valve 12. From this chamber fuel flows through passage 13 to orifice 14 located in the bottom of riser 15, which orifice is regulably controlled in size by needle valve 16 having an adjusting screw head 17 as illustrated. Riser 15 is set vertically in a well 18. The upper end of the riser has an enlarged screw-threaded head 19 threaded into the upper end of the well, and the lower end of the tube has a conical tight fit at 20 with the lower conical end of the well. The upper surface of riser head 19 is cupped to form a small annular trough 19a, to catch any small amount of fuel that might otherwise tend to run along chamber 22 and into the venturi; and to provide a concentration from which the fuel is easily "wiped up" by the current of air passing up through suction tube 37.

Fuel which flows upwardly through primary metering orifice 14 flows upwardly into riser 15 and also flows through orifice 18a into well 18. With the carburetor inactive, fuel stands at the same gravitational level in fuel chamber 10, well 18 and riser 15.

The riser 15 forms a passage through which fuel passes from the metering orifice 14 upwardly to the depression chamber 22, into which the upper end of the riser directly discharges. Depression chamber 22 has communication with the main suction passage of the carburetor, via passage 23 and ports 24. The main suction passage has an air inlet 25, which may have a manual choke valve 26 if desired; a suction outlet 27 controlled by the usual throttle 28; and, intermediate the inlet and outlet, a Venturi passage 29 which is here shown as formed in a separate casting 30 which also closes, or forms one wall of, the annular suction passage 23 referred to. The ports 24 hereinbefore referred to extend through the wall of Venturi casting 30, communicating between passage 23 and the Venturi passage substantially at its point of smallest cross-sectional area.

Suction applied to ports 24, and thus applied to depression chamber 22, is the operating suction which raises fuel through riser 15 and into chamber 22; there to be picked up and carried on by a suction applied to passage 22 from main fuel nozzle 35, as will shortly be described. It may be noted at this point that the amount of suction or depression applied to suction ports 24, and this is dependent on the air velocity through the venturi, is substantially the sole factor in determining the amount of fuel to be lifted to chamber 22, throughout the major range of carburetor action. During idling and accelerating operation other factors come into play, but those actions, and that of the "economizer" system, do not negative the charac-

teristic action of initial fuel metering caused by the Venturi depression.

The provisions for providing accelerating fuel in this carburetor are very simple, involving nothing more than the well 18 surrounding and communicating with the riser 15, as shown. The upper end of well 18 is bled with air through orifice 18a from the float chamber; another orifice 15a communicates air from the upper end of the well, above the fuel level, to riser 15; an orifice 21 at the lower end of the well provides passage for fuel from the well to the riser; and an orifice 18b feeds the well directly from fuel passage 13. The action of the carburetor on acceleration is so simple and positive that no further accelerating provisions are needed.

Another suction passage 36 communicates at one end with the calibrated fuel nozzle 35, and also communicates with depression chamber 22 hereinbefore described. The communication is here shown as formed by a suction tube 37 coaxial with fuel riser 15, the suction tube 37 also surrounding valve stem 16a, as does the riser 15. And this suction tube 37 preferably depends somewhat into depression chamber 22, as shown.

For purposes of providing an idling mixture control in the form of device shown in Figures 1, 5 and 6, passage 36 is provided with a sliding control valve 40. In the actual construction this control valve slides horizontally in a horizontal cylindric chamber 41. In Figure 1 this valve chamber is illustrated as vertical, in order that the complete operative parts of this form of the carburetor may be more nearly shown in a single figure. Figures 5 and 6, however, show the same parts in proper constructional relationship. The operation in both cases is the same or substantially so. Valve 40 has a reduced neck 40a, of smaller diameter than that of suction passage 36, and normally stands across the suction passage, so that normally the suction passage leading to fuel nozzle 35 is open to its widest extent. Valve 40 is pressed to this normal position by a small spring 42 of suitable strength. Valve 40 fits its valve chamber 41 rather loosely (for the "inch and a quarter" size of carburetor here illustrated a suitable looseness of fit is about 0.007 inch in diameter). An idling by-pass passage 44 communicates with valve chamber 41 beyond the end of valve 40, passage 44 communicating with suction outlet 27 at the suction or engine side of throttle 28.

The high suction applied to passage 44 when throttle 28 is closed or nearly closed, causes valve 40 to move across suction passage 36 against the pressure of spring 42, thus partially closing off suction passage 36.

The limit of valve movement toward closed position is fixed by the limiting stop pin 45

of adjustment screw 43; and the typical limiting position is such that valve 40 does not quite close off suction passage 36. On opening the throttle, valve 40 goes back to its normal position, reaching that position typically at something less than half open position of the throttle. Operation of the parts to supply idling mixture will be described in setting out the whole carburetor action, hereinafter.

Located in Venturi passage 29 is a control valve 50, mounted on a vertically sliding valve stem 51 whose lower end is provided with a dash piston 52 operating in dash cylinder 53 kept full of liquid by communication 54 with fuel chamber 10. Valve stem 51 slides in a tubular sleeve 51a whose upper end is above the fuel level; fuel rising around the valve stem lubricates it. The dash piston is made up of a loose perforated disk 55 floating between two stop flanges 56 and 57 on valve stem 51, the lower flange 57 serving to close the disc perforations on the upward stroke. The downward stroke—settling movement of valve 50 from the position of Figure 1 toward the position of Figure 7—is comparatively free and uncheckered. The dash pot action prevents control valve 50 from rising at high velocity under suddenly applied suction, and, together with inertia of the moving parts, makes the valve lag behind the increasing air velocity, so to speak. When throttle valve 28 is opened, even quickly, control valve 50 moves up at retarded velocity; reaching its position of equilibrium, for any given air velocity, after the air flow has reached that velocity; and the valve has little or no tendency to move beyond, or oscillate around, its floating position of equilibrium determined by the amount of suction being applied to it.

In the typical carburetor structure here being described, I have also incorporated a balance tube and an economizer. These elements, although having nothing substantial to do with the present invention, are necessary in practice in a successful carburetor, and will therefore be briefly described. The balance tube comprises a passage 60 communicating between air intake 25 and float chamber 10, to maintain a balance or fixed relationship between the pressure at the intake and that on the fuel in the float chamber.

The economizer system is shown as a passage 61 connecting with balance passage 60 (see particularly Figure 2) and having an adjustable orifice 62 communicating with the main suction passage of the carburetor at a point just slightly below throttle valve 28 in its closed position. As shown in Figure 2 the throttle valve rotates in the direction indicated by the arrow to open; and economizer port 62 located so that, at a minor fractional opening of the throttle, the throttle edge passes downwardly over port 62, thus

communicating that port with the suction outlet 27 above the throttle. By such action, an increased depression from the suction outlet is placed upon port 62, and thus, through passages 61 and 60, on the fuel in the float chamber; such additional depression being more or less suddenly applied as the throttle edge passes port 62 and then gradually disappearing as the throttle is open more widely. The resulting temporary increased depression applied to the fuel chamber causes the thinning of the mixture when the carburetor is acting at partial loads, but does not interfere with idling action or with full power operation when the throttle is wide open. Adjustable valve 63 is used to adjust the effective size of orifice 62.

The economizer system herein described is the subject matter of United States Letters Patent No. 1,799,585, issued Apr. 7, 1931, to O. H. Ensign, on Carburetors; the balance tube is the subject-matter of the O. H. Ensign patent on Carburetor, No. 1,506,229, issued Aug. 26, 1924; and neither are, in themselves, claimed here.

Figure 3 shows modifications of certain parts of the idling system shown in Figure 1. Here the idling bypass port 44a is controllably bled through orifice 44b which communicates with the fuel chamber 10, orifice 44b being regulated by valve 44c. A port 44d leading from passage 44a, communicates with suction passage 36 to pick up and carry off fuel during idling operations.

Figure 4 shows a further modification, somewhat similar to that shown in Fig. 3, except that here the port 44d does not communicate with suction passage 36 but is extended on downwardly by the tube 44e into the fuel chamber 10, the lower end of tube 44e having a restricted orifice 44f at its lower end below the fuel level.

Figures 5 and 6 illustrate also the small choke valve 65 which may be placed across the depression chamber 22 and, manually operated, may be used either as a substitute for, or in conjunction with, choke valve 26 at the air entrance. Choking at either of these points causes a temporarily enriched mixture, as will be readily understood after consideration of the description of action which follows these descriptions of typical structures.

Figures 9 and 10 show another form of carburetor, similar in its action to the form shown in Figure 1, but wherein the suction actuated valve 40 of Figure 1 is replaced by a valve actuated mechanically from the throttle shaft. The valve in Figure 9 operates vertically and has a lower enlarged head 40g mounted on the lower end of a valve stem 40h. This valve plays vertically in a cylindrical bore 41a which crosses suction passage 36. The valve is normally pressed upwardly by a spring 70, its upward limiting position

being determined by a stop collar 71 bringing up against the adjustment screw 72, as shown in Fig. 10. Fig. 10 shows the parts in their idling positions, with the valve in its adjusted uppermost position. Fig. 9 shows the parts in their full open operating positions, with the valve in its lowermost position.

The upper end of valve stem 40h has a head 73 adapted to cooperate with cam 74 on throttle shaft 28a. The shape of this cam is such that, with the throttle in closed or idling position, the valve is in its adjusted uppermost position, choking off suction passage 36 to the extent desired for idling operation (see Fig. 7). When the throttle is moved toward open position, cam 74 acts to press valve 40g downwardly toward the position shown in Fig. 9, reaching that position typically at somewhere around half open throttle. An intermediate position is shown in Fig. 8.

For purposes of more particularly describing these typical structures which have been found efficient in operation, I shall give typical dimensions of the more important operating passages, orifices, and other parts; it will be understood that I do this for the purpose of enabling others to obtain a clear understanding of typical and illustrative embodiments of the invention, and not at all for the purpose of limiting the invention. I believe the invention to be very much broader in its scope than the particular and typical structures herein described; the scope of the invention cannot be understood merely from consideration of the characteristic modes of operation hereinafter set forth. Those characteristic modes of operation require, in the particular structure here described, certain general relationships between various operating parts, and I shall indicate those relationships, as I have found them effective as applied to the particular embodiments herein discussed.

The carburetor shown in the accompanying drawings is of a size known as "inch and a quarter" size.

In a carburetor of the size mentioned, the diameter of the suction outlet is $1\frac{1}{16}$ ". The diameter at the throat of the venturi is $1\frac{1}{16}$ " and the diameter of the guide tube surrounding the valve stem central of the venturi is about $\frac{7}{16}$ ". The annular passage area around valve 50 when in its uppermost or wide open position, is the equivalent of substantially a $1\frac{1}{2}$ " circle; so that the effective wide open area around valve 50 is less than the effective area through the Venturi throat.

Suction ports 24 at the throat of the venturi are six in number and of drill size No. 27, diameter 0.1440 inch. The interior effective area of suction tube 37 equals the area of a $\frac{3}{8}$ inch bore. The effective passage area through suction tube 37 is therefore less than the total areas of suction ports 24. Suction

passage 36 is $\frac{1}{4}$ inch in diameter. In Figure 9, the lower end of idling by-pass 44, where it communicates with suction passage 36, is drill size 50, 0/0700 inch diameter; its upper end, communicating with the suction outlet, is a No. 56 drill. Fuel nozzle 35, drill size No. 14 or 0.1820 inch diameter.

Bleeder opening 18a which leads from fuel chamber to well 18, is drill size No. 51; 10 bleeder opening 15a through the upper end of riser 15 is drill size No. 53, orifice 21 at the lower end of the riser is drill size No. 53, and the auxiliary fuel feed orifice 18b, which leads directly from the fuel chamber to well 15 18 is drill size No. 50.

The weight of the control valve assembly (valve 50 with its valve stem and dash piston) is about $3\frac{1}{2}$ oz.; and the piston disk 55 has two holes of about $\frac{1}{16}$ inch diameter. 20 There is a slight clearance of the piston disk in the dash cylinder, just enough to eliminate a tight fit and any friction.

Operation

25 Referring first to Figures 1, 7 and 8, it will be noted at the outset that control valve 50 rises and falls in accordance with the amount of air (air velocity) passing through the carburetor. At idling the control valve is either 30 in or near its lowermost position, as shown in Figure 7. In this figure the valve is shown just above its lower position, slightly above the depression ports 24. As the air velocity through the carburetor increases valve 50 35 rises higher, taking a position of equilibrium—floating on the air stream, as it were—for any given air velocity. Figure 8 shows the position for approximate half power operation, while Fig. 1 shows position for a 40 full power operation.

The weight of valve 50 and its connected parts, and the relative configurations of the venturi and valve are the main controlling factors in determining the equilibrium position of the valve for any given air velocity and in determining the difference between the depressions applied at the depression ports 24 and at the fuel nozzle 35. The relative configuration such as shown in the drawings have been found to be very successful; 45 and, with the valve of approximately the weight hereinbefore given, a difference of depression, fairly constant, of about 0.4 of an inch of mercury is maintained between the 50 depressions applied at 24 and 35.

The venturi, having at no time any fuel injected into it, becomes in practice exactly what it is in theory—an accurate metering instrument with a substantially straight 60 line fuel metering function. The depression at the throat of the venturi or at depression ports 24 is found in this carburetor to vary almost exactly as a constant function of the air velocity. Consequently, the depression applied in depression chamber 22 and applied

to riser 15 to raise the fuel is always an accurate function of the air velocity; and this results in a certain definite proportion between the amount of air passing through the carburetor and the amount of fuel raised to 70 the upper end of the riser. In other words, the initial metering of fuel is very accurately proportionate, to the amount of air, throughout the range of operation. And this is due to the fact that the metering venturi is not 75 affected or obstructed in its operation by the introduction of any vaporizable or expansible fluid to that venturi.

The fuel having been accurately metered, the next step in the operation of the carburetor is to move the fuel on into the main air passage without allowing it to flow into the Venturi throat and without passing it through the venturi on its way to the air passage. This, in general, is the function of the 80 depression applied to nozzle 35 by the action of control valve 50. I have stated that the control valve acts to apply a nearly constant additional depression at nozzle 35. The important fact is that an additional depression 85 is applied at nozzle 35. It is not necessary that the difference in depressions be constant; it is advantageous, however, that such difference be somewhere near constancy in order that during the normal operating 90 range of the carburetor, the functions as herein described shall be uniformly carried out.

The relatively higher depression applied 100 at nozzle 35 is applied, through suction passage 36 and suction tube 37, to chamber 22 directly over the fuel being lifted through riser 15; and the suction caused by the additional pressure picks up the fuel as fast as it reaches the top of the riser, and carries the 105 fuel (with air) along through tube 37 and passage 36 to nozzle 35, where it is thrown into the main air passage together with air and with a high violence that insures rapid and complete atomization. This rapid and 110 forcible movement of the fuel into the main air stream is due to the fact that there is a substantial depression difference between depression ports 24 and fuel nozzle 35.

During the operation just previously described, and due to the differences in depression, as stated, air is, of course, constantly entering depression ports 24, and flowing with the fuel up through passages 37 and 36 to the nozzle. And, during the complete 115 operation of the carburetor, throughout its range, air always flows outwardly from the Venturi throat through depression ports 24. Neither air nor fuel ever flow inwardly through these ports into the venturi.

In spite of the fact that the higher depression at nozzle 35 is applied to depression chamber 22, the depression in that chamber is controlled by the depression at ports 24 125 because ports 24 act as a relatively wide open 130

bleeder to chamber 22, the aggregate area of ports 24 being substantially larger than the effective area of suction tube 37, or of nozzle. Consequently it is the Venturi throat depression which is normally active to raise and meter the fuel through riser 15; while the nozzle depression is only effective in then raising the fuel from the metering point and carrying it on through the nozzle.

10 Air which bleeds into chamber 22 through depression port 24 is carried on with the fuel to nozzle 35. Also, in normal operation, a certain amount of air is bled into riser 15 through ports 18a and 15a, to be carried on with the fuel. In normal operation the fuel in auxiliary well 18 stands at about or somewhat under the level of fuel in float chamber 10, the port 15a being always above the liquid level to admit air to the 20 upper end of riser 15.

Upon acceleration, sudden opening of throttle 28 and sudden increase in air velocity, control valve 50 does not immediately move to its higher position of equilibrium 25 under the new conditions, but moves up sluggishly, retarded by its own inertia and the dash pot action. During the period of acceleration, the excess depression applied to nozzle 35 is increased over the normal amount; and that temporary excess of depression, applied to chamber 22 via suction tube 37, places on chamber 22 and on fuel riser 15 a temporarily greater than normal depression. This abnormally great depression 30 raises fuel in greater than normal quantity through the riser and thus calls on the accelerating supply in well 18; drawing that supply through port 21 from the well into the lower end of the riser. The increased 35 fuel flow is carried on by the nozzle and flows into the main air stream with increased violence due to the increased differential depression; this fuel reaches the main air stream somewhat before valve 50 has risen to its new point of equilibrium and therefore before the main air stream has increased to its new volume. The result is that, upon acceleration, the additional amount of fuel desired for acceleration instead of lagging 40 behind the air stream increase, is actually thrown into the air stream ahead of the air stream increase. This provides for most effective acceleration mixtures.

Once acceleration has been accomplished 45 and the parts of the carburetor have assumed their normal positions of equilibrium, the accelerating well will more or less fill up to provide for any successive acceleration, provided the carburetor is being operated 50 in its intermediate range. However, as the carburetor approaches its higher ranges, the increased constant depression applied to the fuel riser gradually drains more and more fuel from the auxiliary well at the higher 55 ranges until the fuel is exhausted from the

well and air then passes through the well and into the lower end of the riser through port 21.

The action of the well itself is thus seen to be similar to that of previous accelerating wells. It is to be noted, however, that the action of control valve 50, and the differential depressions caused by that action, are effective factors causing the characteristic accelerating operation here described. And the operation is so simple that the simple accelerating well here shown is most highly effective, and it is not necessary to have any of the usual complicated system of bleeds, small ports liable to clog up, compensating systems, etc., which are usually found necessary in connection with accelerating wells in the ordinary carburetor.

Speaking of operation at the highest ranges, it may be noted that the carburetor is not limited to operation with control valve 50 floating on the air stream. When the control valve reaches its upper limit of movement, as shown in Figure 1, the carburetor will still continue to operate successfully, only limited by its capacity as measured by size. When the air valve reaches its upper limiting position, the metering function of the Venturi throat is still operative. The differential depression between nozzle 35 and depression ports 24, is of course, increased as the air flow increases; but this simply means that an additional differential depression is available for final transport of the fuel into the air stream.

In a carburetor designed and operating as has been described it is found that the nozzle depression is too great for idling operation. During idling operation the depression ports 24 are quite wide open; they are never completely closed off. In its lowermost position control valve 50 fits snugly, although not tightly in the Venturi throat; so that in its slightly raised position, as shown in Figure 7, a little air can pass the valve, and a relatively heavy depression is placed on nozzle 35. This depression, bled by the depression ports 24, is sufficient to raise much more fuel than the small amount required for idling operation. However, the system lends itself readily to modification for idling function; and in the form of Figure 1 this modification is accomplished by the valve 40.

In the preceding description of carburetor operation throughout its normal running range, it has been assumed that valve 40 is in or about the positions of Figure 1, with suction passage 36 open. As throttle 28 is closed down, and after it reaches a point something under half open, the suction applied to idling by-pass 44 begins to move valve 40 against the pressure of spring 42, so as to gradually close off suction passage 36. As the throttle is closed further, this action of valve 40 proceeds more strongly

until, when throttle 28 is closed down to idling position valve 40 has been drawn across passage 36 to the limiting position determined by the setting of stop pin 45. A 5 typical limiting position is one in which valve 40 closes passage 36 down to about one-third its normal cross sectional area.

In this last described position of valve 40 the suction applied to suction tube 37 from nozzle 35 is thus modified to draw up just 10 the amount of fuel required for idling operation. During this idling operation it is the suction from nozzle 35 which predominates in suction chamber 22, although that 15 chamber is still bled by the depression ports 24. The fuel drawn up and metered by the controlling suction thus applied to suction tube 37, is then taken on into the engine intake through idling passage 44, the depression 20 in 44 being much lower than the controlled depression in suction passage 36. Consequently the depression in passage 44 draws the metered fuel by the loosely fitting valve 40 and on through passage 44 into the 25 engine intake at the suction side of the throttle. Air for the idling mixture is, of course, being drawn through ports 18a, 15a, and 24, and to some extent through the venturi past control valve 50.

30 From what has been said it can be understood how the Venturi depression is a controlling and practically the sole factor in metering fuel during normal carburetor operation and throughout the range; excepting 35 only during idling operation and acceleration. During these last two mentioned operations the suction at nozzle 35 predominates and controls; but at no time does any fuel enter the metering venturi. The fit of 40 valve stem 51 in its bearing sleeve 51a is tight enough that the relatively thin volume of fuel would serve to lubricate the valve stem is either not drawn from the upper end of the bearing sleeve by suction or is drawn 45 in such small amounts as not to vitiate accuracy and efficiency of operation.

For some installations it has been found 50 unnecessary to provide the idling arrangements shown in Figures 1 or 9. For instance, as shown in Fig. 3, the idling passage 44a is adjustably bled at 44b by air from the fuel chamber, thereby to modify the depression in passage 44a when the throttle is closed; and the lateral passage 44d picks up the fuel 55 from the nozzle passage 36. This arrangement and the one shown in Fig. 4 operate satisfactorily where the conditions are such that an excessive depression on nozzle 35 is not caused when the engine is idling.

60 Figure 4 shows a similar arrangement and one herein the depression of passage 44a picks up fuel directly from float chamber 10. Its action will be understood readily without further description.

65 From what has now been described, the

operation of the form shown in Figures 9 and 10 will be largely understood without necessity of repetition. Here the valve 40g is mechanically operated to perform the same depression throttling function as before described. The valve in Figure 9 operates vertically; so that when it is in its uppermost position (Fig. 7) shutting off passage 36, the fuel lifted to passage 36 by the modified suction from fuel nozzle 35 is more or less 70 held in passage 36 behind passage 40g; and the higher suction applied during idling through the idling passage 44j picks up the fuel directly from suction passage 36. Otherwise the operation is the same as before described. 75

It will be understood that neither the order in which various forms of carburetors and modifications have been described, nor the extent of description applied to various figures of the drawings, is to be taken as an indication of any fundamental preference. All of the forms here described have been found to have desirable features. On the whole, the form of Fig. 9 appears at present 80 to give the most completely satisfactory operation under all circumstances.

Within limits prescribed by its size, the carburetor which I have now described is 85 universally applicable to any kind and size of engine without the necessity of any material change in design or construction. It is only necessary, when placing this carburetor on different engines, to set the three 90 adjustments; it is not necessary to redesign 100 the carburetor to suit any particular "job". The carburetor of a size suitable for a given 105 size engine may be taken off and applied to an engine of much smaller size and operate perfectly, sometimes without even making further adjustments. This statement applies equally to engines of any number of cylinders and cylinder displacements, character of suction curve, manifold arrangements, etc.

In applying the carburetor to any engine, it is only necessary for most efficient performance to make the three adjustments hereinbefore described. Adjusting screw 17 is set 115 to control the wide open mixture; adjusting screw 43 is then set to control the idling mixture; and then adjusting screw 63 is set to control the operation of the economizer. After setting the economizer adjustment it 120 may be desirable slightly to readjust the main mixture setting. When once adjusted, this carburetor has been found to produce very efficient results, both as to economy of operation and as to power. Both economy of operation and power results are largely 125 due to the fuel metering functions as described; and the power production is very marked when an engine is operating wide open at low speed. And, furthermore, the carburetor, because of its peculiar and char- 130

acteristic action during acceleration gives to an engine very high power characteristics during pick up.

The forms of Venturi tubes shown in Fig. 7 and Fig. 11 have been designed especially to attain efficiently the functions herein described. At their lower ends these venturis have a "streamline" curved constriction A leading up to the throat where ports 24 are located; so that the velocity caused depression at the throat is attained without undue frictional losses.

Upwardly from the throat the wall curve starts first substantially straight up—the increase in area on upwardly progressing cross-sections is at first comparatively small. In Fig. 7 this part of the curve is designated B in Fig. 7. In Fig. 11 the corresponding part of the curve is designated B1. In this latter figure the curve B1 has a first part, immediately above the throat, which is strictly vertical; in the design there shown the venturi is of constant diameter for about three-sixteenths of an inch measured upwards from the centers of ports 24.

Above the curve B or B1, the wall curve of the venturi curves as at C increasingly outwardly—the area here on upwardly progressing cross-sections increases at an increasing rate—until the point of greatest area is nearly reached, when the curve reverses, as at D, to obtain a smooth streamline flow around valve 50 when in its uppermost position.

I have before mentioned the fact that the cross-sectional flow area around valve 50, in its uppermost position, is somewhat less than the area at the Venturi throat. The outer edge portions of the valve are convexly curved, in vertical section, as shown at E; and the upper face of the valve is concavely curved, as at F. These two valve curvatures form, with the reverse (concave) curvature D and the uppermost convex curvature G of the air passage, an upwardly expanding annular passage, around the valve, with smoothly curved walls and gradual expansion of area to lead the fluids up to the carburetor outlet with small frictional or eddy loss and at minimum depression.

Actual observations of the fuel and air mixing action taking place in the air passage in the zone directly above the valve, indicate that the high efficiency of the carburetor results not only from efficient metering and economical proportioning of the fuel, as above described, but also from the provision of a fuel and air mixing action of such efficiency as to approach, in the final mixture taken into the engine complete atomization of the fuel. In a carburetor specially set up for test purposes, I have observed that by virtue of the illustrated configurations given the air passage wall above the Venturi throat, and the valve itself, a

turbulence and annular eddying of the air stream is developed which produces, in addition to the effect of high velocity discharge of fuel and air from nozzle 35, fine division and atomization of the fuel, and separation from the final fuel and air mixture of any fuel particles of appreciable size, or such particles as are incapable, because of their size, of floating on the air stream.

My observations have indicated that the air stream at all open positions of the valve, and after passing above the periphery of the valve, follows initially a path of flow along the inwardly curved wall surface G, and that because of the curvature or inward deflection of this surface, the air stream, or at least a part of air stream, is caused to eddy radially inwardly from the upper extent of this surface and to reverse its flow and pass downwardly along the top curved surface F of the valve. Thus an inwardly and downwardly eddying flow of air is established in the upwardly diverging space between the top surface of the valve and the surrounding fuel and air passage wall. In order to explain more clearly the nature of the eddying air stream in the divergent space above the valve, I may state that my observations have indicated the physical condition of this eddying current of air to be similar to a smoke ring in which the smoke particles are whirling radially and downwardly inward toward the center of the ring. Here the center of the ring-shaped eddying air current is at the radial center of the air passage, or the central upper end portion of the valve.

An initial division and atomization of the fuel occurs by virtue of the high velocity discharge into the air stream flowing upwardly past the valve, of fuel and air from nozzle 35, and due to this high velocity discharge, the fuel from nozzle 35 is effectively distributed in a horizontal direction entirely around the valve. A second division and atomization of the fuel particles, and a separation from the final fuel mixture taken into the engine, of any fuel particles of appreciable size, takes place as the fuel particles are carried into the eddying and turbulent zone in the divergent space between valve surface F and the wall surface G. The air turbulence set up in this zone has the effect of causing the fuel in the final mixture to approach ideal complete atomization, by two actions. First, as soon as the fuel particles from nozzle 35 are carried into the turbulent air zone, atomization of the particles takes place due to their being subjected to a more or less violent agitation in the air passage. Second, any particles of appreciable size are carried by the eddying air stream radially inward to the relatively quiescent and substantially less turbulent zone at the center of the air passage directly above the valve cen-

ter, wherein such particles settle onto the down-sloping surface of the valve and then become swept into the downwardly eddying air stream and again subjected to atomization as they are picked up by the high velocity air stream flowing up past the valve. It will be seen that this last described operation is essentially one of separation of the large particles from small or atomized particles, and that this operation contributes to the forming of a final atomized fuel and air mixture, in that it acts to move the undesirably large particles from the fuel that has been subjected to atomization in the manners stated, and to permit only those particles in such fine state of division or atomization as to be capable of floating in the air stream, to pass out in the final fuel and air mixture.

20 For most successful results, the fuel nozzle 35 preferably is placed in such position, relative to the valve, that when the valve is in its uppermost position, the center of the nozzle bore will be substantially opposite or 25 slightly above the peripheral surface of the valve at the point of maximum diameter. Satisfactory results may be had by arranging the valve and nozzle in the relative positions shown in Fig. 1.

30 It will thus be seen that the venturi, the air passage and the valve are so shaped as to perform their desired functions with minimum losses of pressure in the flowing air stream. Additionally, however, the configurations here described, perform another function which I note particularly. I have spoken of the fact that, on opening the throttle, retardation of upward valve (50) movement causes a temporarily higher depression 40 to be applied to feed fuel at a temporarily higher proportion. Due to the fact that in the lower part of its upward travel the valve must move upwardly a greater distance, to increase the air stream cross-section by unit 45 amount, than in the upper part of its travel; the valve action is thus to temporarily give a relatively richer mixture when the throttle is quickly opened during "low" carburetor operation than during "high" carburetor operation. That is a desirable feature; among other things it promotes quick starting of a cool engine and high power on quick acceleration particularly at or from the lower ranges of operation.

50 Considering these things, the functional difference between Fig. 7 and Fig. 11 will be recognized. The actions just spoken of are more pronounced in Figs. 11 and 12, where the retarded valve has to rise a short distance before it begins 55 at all to increase the air passage area. Thus, from the standing condition of Fig. 11, valve 50 rises substantially toward the position of Fig. 8 even for idling—it has to rise somewhat above the straight wall surface B1 in 60 order to increase the area at all. Conse-

quently the design of Fig. 11 has all the characteristics of Fig. 7, plus an action tending temporarily to make a still richer mixture at idling or very low range.

It will be understood that where I refer to applying pressure (or depression) from the air passage intake to the fuel chamber, I do not mean to limit myself to the particular arrangement here illustrated and described. Such a balance passage as I have described is merely a means to compensate the whole carburetor action for any variations in intake pressure, such as are commonly due to altitude, the use of a dust strainer or heating "stove", etc., on the intake. With a wide open intake the pressure through the balance passage to the fuel chamber is practically atmospheric; and under those conditions the carburetor will function properly with the fuel chamber open to atmosphere— 35 that is, taking the pressure which is present at the mouth of the air intake.

On the other hand, the carburetor here described will function properly if the fuel chamber pressure be taken off the air passage at some point where the pressure is less than that of the intake; provided only that the other two pressures—that on the depression passage 22 and that on the fuel nozzle— 40 be proportioned accordingly, so as to keep 45 the two pressure differentials, for metering fuel and for finally feeding fuel, in proper amounts and relation.

Accordingly, the arrangements for applying the different depressions, as herein described, can be broadly considered as involving means for taking three different pressures or depressions off the air passage at different points in the passage, without any limitation on the particular places of pressure take-off, or the methods or means of creating the differences in pressure. More particularly, however, I find it of practical importance that the second pressure difference (the differential between depression passage 100 22 and nozzle 35) should be substantially 105 uniform throughout the range of operation when the carburetor is operating in equilibrium; but that during changes of operating speed this second pressure differential 110 115 should vary as I have described.

I claim:

1. In a carburetor having an air passage with a venturi, a fuel chamber, and a depression chamber in fuel communication with the fuel chamber, the combination of means to apply pressure to the fuel chamber, means to apply a lower pressure from the throat of the venturi to the depression chamber, a fuel nozzle communicating with the depression chamber and discharging into the air passage at a point removed from the Venturi throat, and means in the air passage to create at the fuel nozzle a pressure lower than that at the Venturi throat, said last mentioned means in- 120 125 130

cluding a valve floating on the air current in the venturi and adapted to be moved by the air current from a position approximately closing the Venturi throat to a position further along the venturi in the direction of air flow, the venturi having a flare, extending from its throat in the direction of air flow, and the cross-sectional area of the flare increasing at an increasing rate in said direction.

2. In a carburetor having an air passage with a venturi, a fuel chamber, and a depression chamber in fuel communication with the fuel chamber; the combination of means to apply pressure to the fuel chamber, means to apply a lower pressure from the throat of the venturi to the depression chamber, a fuel nozzle communicating with the depression chamber and discharging into the air passage at a point removed from the Venturi throat, and means in the air passage to create at the fuel nozzle a pressure lower than that at the Venturi throat, said last mentioned means including a valve floating on the air current in the venturi and adapted to be moved by the air current from a position approximately closing the Venturi throat to a position further along the venturi in the direction of air flow, the venturi having at its throat a portion of substantially uniform cross-sectional area extending in the direction of air flow, and then, extending further in the direction of air flow, having a flare whose cross-sectional area increases at an increasing rate in said direction.

3. In a carburetor having an air passage with a venturi, a fuel chamber, and a depression chamber in fuel communication with the fuel chamber; the combination of means to apply pressure to the fuel chamber, means to apply a lower pressure from the throat of the venturi to the depression chamber, a fuel nozzle communicating with the depression chamber and discharging into the air passage at a point removed from the Venturi throat, and means in the air passage to create at the fuel nozzle a pressure lower than that at the Venturi throat, said last mentioned means including a valve floating on the air current in the venturi and adapted to be moved by the air current from a position approximately closing the Venturi throat to a position further along the venturi in the direction of air flow, the venturi having a flare, extending from its throat in the direction of air flow, and the cross-sectional area of the flare increasing at an increasing rate in said direction, and the valve fitting the venturi closely at the throat.

4. In a carburetor having an air passage with a venturi, a fuel chamber, and a depression chamber in fuel communication with the fuel chamber; the combination of means to apply pressure to the fuel chamber, means to apply a lower pressure from the throat of

the venturi to the depression chamber, a fuel nozzle communicating with the depression chamber and discharging into the air passage at a point removed from the Venturi throat, and means in the air passage to create at the fuel nozzle a pressure lower than that at the Venturi throat, said last mentioned means including a valve floating on the air current in the venturi and adapted to be moved by the air current from a position approximately closing the Venturi throat to a position further along the venturi in the direction of air flow, the venturi having at its throat a portion of substantially uniform cross-sectional area extending in the direction of air flow, and then, extending further in the direction of air flow, having a flare whose cross-sectional area increases at an increasing rate in said direction, and the valve fitting the venturi closely at the throat.

5. In a carburetor having an air passage with a venturi, a fuel chamber, and a depression chamber in fuel communication with the fuel chamber; the combination of means to apply pressure to the fuel chamber, means to apply a lower pressure from the throat of the venturi to the depression chamber, a fuel nozzle communicating with the depression chamber and discharging into the air passage at a point removed from the Venturi throat, and means in the air passage to create at the fuel nozzle a pressure lower than that at the Venturi throat, said last mentioned means including a valve floating on the air current in the venturi and adapted to be moved by the air current from a position approximately closing the Venturi throat to a position further along the venturi in the direction of air flow, the venturi having, extending from its throat, a flare whose cross-sectional area increases at an increasing rate in the direction of air flow, the valve having a convexed outer edge and a concaved stream-lined surface toward the outlet, and the air passage beyond the venturi having a stream-lined surface which, with the valve surface, defines an expanding passage for the flowing air.

6. In a carburetor having an air passage with a venturi and a throttle at the outlet side of the venturi, a fuel chamber, and a depression chamber in fuel communication with the fuel chamber; the combination of means to apply pressure to the fuel chamber, means to apply a lower pressure from the Venturi throat to the depression chamber, a fuel nozzle communicating with the depression chamber and discharging into the air passage at a point removed from the Venturi throat, means in the air passage to create at the fuel nozzle a pressure lower than that at the Venturi throat, an idling by-passage leading from a point in the air passage outlet beyond the throttle to the communication of the fuel nozzle with the

depression chamber, and means actuated by virtue of throttle closure to close off said communication.

7. In a carburetor having an air passage with a venturi and a throttle at the outlet side of the venturi, a fuel chamber, and a depression chamber in fuel communication with the fuel chamber; the combination of means to apply pressure to the fuel chamber, means to apply a lower pressure from the Venturi throat to the depression chamber, a fuel nozzle communicating with the depression chamber and discharging into the air passage at a point removed from the Venturi throat, means in the air passage to create at the fuel nozzle a pressure lower than that at the Venturi throat, an idling by-passage leading from a point in the air passage outlet beyond the throttle to the communication of the fuel nozzle with the depression chamber, and means actuated by virtue of throttle closure to close off said communication at a point between the nozzle and the by-passage.

8. In a carburetor having an air passage with a venturi and a throttle at the outlet side of the venturi, a fuel chamber, and a depression chamber in fuel communication with the fuel chamber; the combination of means to apply pressure to the fuel chamber, means to apply a lower pressure from the Venturi throat to the depression chamber, a fuel nozzle communicating with the depression chamber and discharging into the air passage at a point removed from the Venturi throat, means in the air passage to create at the fuel nozzle a pressure lower than that at the Venturi throat, an idling by-passage leading from a point in the air passage outlet beyond the throttle to the communication of the fuel nozzle with the depression chamber, a valve controlling the communication of the fuel nozzle with the depression chamber and located in the communication between the fuel nozzle and the by-passage, and mechanical means for actuating said valve upon opening and closing movement of the throttle.

9. In a carburetor having an air passage with a venturi and a throttle at the outlet side of the venturi, a fuel chamber, and a depression chamber in fuel communication with the fuel chamber; the combination of means to apply pressure to the fuel chamber, means to apply a lower pressure from the Venturi throat to the depression chamber, a fuel nozzle communicating with the depression chamber and discharging into the air passage at a point removed from the Venturi throat, means in the air passage to create at the fuel nozzle a pressure lower than that at the Venturi throat, an idling by-passage leading from a point in the air passage outlet beyond the throttle to the communication of the fuel nozzle with the depression chamber, a valve controlling the

communication of the fuel nozzle with the depression chamber, and means whereby depression at the outlet side of the throttle causes actuation of said valve.

10. In a carburetor, an air passage having an intake and an outlet with an intermediate venturi and a throttle between the venturi and the outlet, the venturi having at its inlet side a stream-lined constriction leading to its throat and at its outlet side leading from its throat a flare whose cross-sectional area increases at an increasing rate toward the outlet, a fuel chamber, a depression chamber in suction communication with the venturi at its throat, a fuel riser leading from the fuel chamber to the depression chamber, a fuel nozzle discharging into the air passage at a point beyond the Venturi flare, a passage connecting the fuel nozzle and the depression chamber and including a riser entering the depression chamber directly over the aforementioned fuel riser, and a valve floating on the air stream in the air passage and movable from a position substantially closing the Venturi throat to a position toward the outlet.

11. In a carburetor, an air passage having an intake and an outlet with an intermediate venturi and a throttle between the venturi and the outlet, the venturi having at its inlet side a stream-lined constriction leading to its throat and at its outlet side leading from its throat a flare whose cross-sectional area increases at an increasing rate toward the outlet, a fuel chamber, a depression chamber in suction communication with the venturi at its throat, a fuel riser leading from the fuel chamber to the depression chamber, a fuel nozzle discharging into the air passage at a point beyond the Venturi flare, a passage connecting the fuel nozzle and the depression chamber and including a riser entering the depression chamber directly over the aforementioned fuel riser, a valve floating on the air stream in the air passage and movable from a position substantially closing the Venturi throat to a position toward the outlet, and means to retard movement of said valve toward the outlet.

12. In a carburetor, an air passage having an intake and an outlet with an intermediate venturi and a throttle between the venturi and the outlet, the venturi having at its inlet side a stream-lined constriction leading to its throat and at its outlet side leading from its throat a flare whose cross-sectional area increases at an increasing rate toward the outlet, a fuel chamber, a depression chamber in suction communication with the venturi at its throat, a fuel riser leading from the fuel chamber to the depression chamber, a fuel nozzle discharging into the air passage at a point beyond the Venturi flare, a passage connecting the fuel nozzle and the depression chamber and including a riser en-

- tering the depression chamber directly over the aforementioned fuel riser, and a valve floating on the air stream in the air passage and movable from a position substantially closing the Venturi throat to a position toward the outlet, the valve having a convexed outer edge and a concaved stream-line surface toward the outlet, and the air passage beyond the venturi having a stream-lined surface which, with the valve surface, defines an expanding passage for the flowing air.
13. In a carburetor having a fuel chamber, an air passage with a venturi, and a fuel nozzle discharging into the air passage at a point removed from the Venturi throat; a depression chamber in communication with the Venturi throat to take a depression therefrom, a fuel riser leading from the fuel chamber into the depression chamber, another riser leading out of the depression chamber from a point directly over the fuel riser and connecting with the fuel nozzle, and means in the air passage to establish on the fuel nozzle a depression greater than that at the Venturi throat.
14. In a carburetor having a fuel chamber, an air passage with a venturi, and a fuel nozzle discharging into the air passage at a point removed from the Venturi throat; a depression chamber in communication with the Venturi throat to take a depression therefrom, a fuel riser leading from the fuel chamber into the depression chamber, another riser leading out of the depression chamber from a point directly over the fuel riser and connecting with the fuel nozzle, and means in the air passage to establish on the fuel nozzle a depression greater than that at the Venturi throat, said means acting to maintain a substantially uniform difference in depression throughout the range of carburetor operation and varying air velocities through the air passage.
15. In a carburetor, the combination comprising, walls forming an air passage having a venturi and an outlet beyond the venturi, said passage having an annular concave wall, one portion of which is formed by a flare in said venturi, extending from the Venturi throat in the direction of air flow, a valve floating on the air current in said passage and positioned within said annular concave wall thereof, said valve being adapted to be moved by the air current from a position close to the Venturi throat to a position further along the venturi in the direction of air flow, and the valve having a convexed outer edge and a stream-lined surface toward the outlet, a fuel chamber, and means for delivering fuel from said chamber to the air passage at a point beyond the throat of the venturi in the direction of air flow.
16. In a carburetor, the combination comprising, walls forming an air passage having a venturi, and an outlet beyond the venturi, said passage having an annular concave wall, one portion of which is formed by a flare in said venturi, extending from the Venturi throat in the direction of air flow, a valve floating on the air current in said passage and positioned within said annular concave wall thereof, said valve being adapted to be moved by the air current from a position close to the Venturi throat to a position further along the venturi in the direction of air flow, walls forming an annular depression chamber surrounding the venturi, a plurality of circularly spaced openings leading from said chamber into the throat of the venturi, means for supplying fuel to said depression chamber, and means for delivering fuel from the depression chamber to the air passage at a point beyond the throat of the venturi in the direction of air flow.
- In witness that I claim the foregoing I have hereto subscribed my name this 20th day of November 1930.
- PAUL W. ENSIGN.
